UNITED STATES PATENT OFFICE

102,853

DESIGN FOR A COMBINATION CIGARETTE BOX AND ASHTRAY

Charles Le Roy Gunther and Philip K. Paval,
Los Angeles, Calif.

Application November 10, 1936, Serial No. 65,832

Term of patent 14 years

To all whom it may concern:

Be it known that we, Charles Le Roy Gunther and Philip K. Paval, both citizens of the United States, and both residing at Los Angeles, in the county of Los Angeles and State of California, have invented a new, original, and ornamental Design for a Combination Cigarette Box and Ashtray, of which the following is a specification, reference being had to the accompanying drawing, forming part thereof, in which

Fig. 1 is a perspective view of a combination cigarette box and ashtray in open position showing our new design.

Fig. 2 is a similar view of the same in closed position.

Fig. 3 is a central transverse section taken on the line 3—3 of Fig. 2.

We claim:

The ornamental design for a combination cigarette box and ashtray as shown and described.

CHARLES LE ROY GUNTHER.
PHILIP K. PAVAL.
